UNITED STATES PATENT OFFICE.

ARTHUR T. BOUCH, OF McGEE'S MILLS, PENNSYLVANIA.

RAILROAD TIE.

Application filed October 15, 1923. Serial No. 668,750.

To all whom it may concern:

Be it known that I, ARTHUR T. BOUCH, a citizen of the United States, residing at McGees Mills, in the county of Clearfield 5 and State of Pennsylvania, have invented certain new and useful Improvements in Railroad Ties, of which the following is a specification.

The present invention relates to a railroad tie and has for its principal object to provide means in combination with a tie for securing rails thereto.

The invention aims to provide a simple and efficient means whereby the tie may be secured to the rails without the necessity of using spikes and the like.

Another object of the invention is to provide a device of this nature having a simple and efficient construction, one which is reliable, easy to manipulate, durable, and well adapted for the purpose designed.

With the above and numerous other objects in view, which will appear as the description proceeds, the invention resides in the novel features of construction and in the combination and arrangement of parts as will be hereinafter more fully described and claimed.

In the drawings:

30 Figure 1 is a top plan view of the tie embodying my invention;

Figure 2 is a side elevation thereof;

Figure 3 is a fragmentary longitudinal section therethrough; and

35 Figure 4 is a transverse section taken substantially on the line 4—4 of Figure 3.

Referring to the drawing in detail it will be seen that the tie is provided with a body 1 of elongated box-like construction. A

40 pair of fixed clamp members 2 are disposed on the upper side of the body 1 adjacent the ends thereof. A pair of tenons 3 are disposed on the upper side of the body 1 between the fixed clamp members 2 and

45 in spaced relation thereto and to each other. A pair of slidable clamp members 4 are constructed with grooves for receiving the tenons 3. These tenons 3 are preferably trapezoidal in cross section and the grooves conform in shape thereto so that there is a dove-tail slidable connection between the body 1 of the tie and the movable or slidable members 4. A pair of links 7 are disposed between the adjacent ends of the slidable members 4. One link 7 is pivoted to

each member 4. The links are pivoted together and thus when the links are lifted at the point where they are pivoted together the slidable jaws 4 will move away from the fixed member 2 whereas when the pivot points of the links where they are connected together are forced downwardly these slidable members will move toward the fixed members 3. The members 4 are so shaped as to engage the base of the rails 8. 60 Any suitable means may be used for holding the links 7 downwardly on the tie body.

The tie can be constructed of metal and thus will be durable having a great length of life. It will be furthermore seen that 70 the rails may be readily disengaged therefrom when it is necessary to renew or repair them.

While the preferred embodiment of the railroad tie has been described in detail, it 75 will be understood that I do not wish to be limited to the particular construction set forth, since various changes in the forms, materials and proportions, and arrangement of parts and in the details of construction may be resorted to without departing from the spirit or scope of the invention or sacrificing any of its advantages.

What is claimed is:

1. A railroad tie of the class described including a body, fixed jaws on the body, tenons rising from the body, slidable jaws provided with mortises for receiving the tenons, one slidable jaw associated with each fixed jaw, links disposed between the 80 slidable jaws whereby they may be moved in operative or inoperative association with the fixed jaws, said tenons being trapezoidal in cross section and said mortises shaped to conform therewith. 95

2. A railroad tie of the class described including a body, a pair of fixed jaws provided on the body, a pair of tenons disposed between the fixed jaws on the body of dovetail formation, a pair of slidable jaws provided with dove-tailed mortises for receiving the tenons, and a pair of links one pivoted to each movable jaw and pivoted at adjacent ends to each other whereby the latter pivoted ends may be raised and lowered for moving the movable jaws away from and toward the fixed jaws all in the manner and for the purpose specified. 105

3. A railroad tie of the class described including a body, fixed clamp members on 110

the body, slid able clamp members engaged with the body between the fixed clamp members so that said slid able clamp members may not be lifted from engagement with the body but move longitudinally thereof toward and away from the fixed clamp members, and a pair of links one pivoted to each slid able clamp member, said links pivoted together and adapted to lie flat on the body so as to hold the slid able clamp-members in operative association with the fixed clamp members so that rails may be held

therebetween and so that the adjacent ends of the links may be lifted causing the slid able clamp members to move toward each other and away from the fixed clamp members for releasing the rails.

In testimony whereof I affix my signature in presence of two witnesses.

ARTHUR T. BOUCH.
